UNITED STATES PATENT OFFICE.

PAUL ERKENS, OF DUREN, GERMANY.

MULTIPLE-WIRE PAPER MACHINE.

Application filed January 23, 1925, Serial No. 4,250, and in Germany November 21, 1924.

My invention relates to multiple wire paper machines.

It is an object of my invention to provide a paper making machine in which a plurality of units, each provided with a Fourdrinier wire, that is, a wire cloth for forming a paper web, are combined with a main wire which may also carry a web. The web or webs from the several units are deposited in succession on the main wire or on the web carried thereon, so that at the end of the machine a combined web is formed, the number of webs therein being equal to the number of units plus the web on the main wire, if there is any. The several units cooperating with the main wire are independent from one another and the webs leaving said units are subjected to the action of suction boxes arranged below the front rolls of each unit.

Preferably all the units and the main wire are subjected to shaking motion in the same direction and in parallel and the compensating shaking motion is imparted to the wire only at the rear of the last unit.

As the units are arranged above the main wire, there is no danger of the web becoming detached from the main wire as is the case in the existing machines where the web adheres to the lower face of the wire.

In the drawings affixed to this specification and forming part thereof, a machine embodying my invention is illustrated diagrammatically by way of example.

In the drawings, Fig. 1 is a partly sectional elevation, Fig. 2 is a plan view of my machine, and Fig. 3 is an end elevation viewed from the left in Fig. 1.

Referring now to the drawing, A is the front main frame stay of the machine which resembles a portal, B is a frame arranged at the left of the frame A and supporting mechanism for actuating my machine, as will be described below, 11 is the table of a size carriage, not shown, 10 is a front cylinder arranged in front of the portal A, a rear cylinder being provided at the rear end of the machine, which is not shown, 13, 13 and 14, 14 are supporting and guiding rollers for the upper and lower reaches of the main Fourdrinier wire 1, 15, 15 are the bars of a shaking frame, 18, 18 are stationary bars to which the bars of the shaking frame are

pivoted at 19, 19, and 12, 12 are clamping cylinders arranged in suitable bearings 12' at the end of the shaking frame just before the pivots 19, 19.

2, 3 and 4 are separate units carried in suitable frames 17 which are built up on the frames 15. Each unit comprises a front cylinder 5 the shaft 16 of which is carried in slotted bearings of the frame 17, a rear cylinder 6, a wire 7 running on said cylinders, and a suction box 8 at the rear of the cylinder 5. Each unit is supplied with paper pulp from a suitable hopper, not shown, and a web is formed on each unit, and combined with a web on the main wire 1. The direction in which the webs on the several units and the web on the main wire 1 are moving, is indicated by the arrows in Fig. 1.

Suction boxes 9, 9 are arranged below the main wire 1 at the points where each unit delivers its web to the main wire 1.

20 is a driving shaft extending along the shaking frame 15, 15, 21 are eccentrics or cams on the shaft 20, 22 are rods taken from the eccentrics to one of the bars 15, 23 and 24 are conical pulleys in the frame B, the pulley 24 being secured on the shaft 20, and 25 is a belt connecting the two pulleys. Rotation is imparted to the pulley 23 by suitable means, not shown, and the belt 25 is shifted on its pulleys 23, 24 by other suitable means, not shown.

By the means described which are below the units 2, 3, 4 are the frames 15, 15 shaken in the same direction as the units.

By depositing the webs from the several units on the wire or on the webs which are already on the sieve, paper or card board consisting of a plurality of webs is obtained, the webs being connected with each other by action of the suction boxes.

If it be desired for instance to make triplex paper for paper bags the first unit 2 will deliver to the main wire 1 a web of high-class pulp of any desired color, for instance white. This web is subjected to the action of the first suction box 9 and fed to the unit 3 by the wire 1 which deposits thereon a web of low-grade pulp. Both webs are firmly connected by the action of the second suction box 9 and fed to the last unit 4 which deposits on the two webs a web of high quality pulp which may be blue. This web is also firmly connected with the

two webs previously formed and a combined web is fed to the clamping rolls 12, 12.

In this manner I obtain paper or card board consisting of two high grade webs 5 and a low grade intermediate web.

Obviously any number of units may be provided, for instance, the first units 2 may be dispensed with and replaced by the size carriage and the table 11.

- 10 In the same manner thick card board can be made on the machine with a corresponding number of units, each of which delivers a web to the main wire 1 or the web or webs which are fed by the main wire 1. Card
- 15 board of any desired thickness can be manufactured in this manner as there is no danger of the web becoming detached from the main wire which at the same time acts as a belt conveyor. Where the web adheres to
- 20 the lower surface of the main wire, as in the machine heretofore used, the danger of the

web becoming detached, obviously increases in proportion to its thickness.

I wish it to be understood that I do not desire to be limited to the exact details of 25 construction shown and described, for obvious modifications will occur to a person skilled in the art.

I claim:

A multiple wire paper machine comprising 30 a principal Fourdrinier wire and a plurality of machine units each comprising a subsidiary wire and adapted to prepare a web of pulp which is delivered to said Fourdrinier wire, said units being adapted 35 to be shaken in unison and in parallel with each other and with that reach of the Fourdrinier wire with which they are cooperating.

In testimony whereof I affix my signature.

PAUL ERKENS.
